UNITED STATES PATENT OFFICE

102,391

DESIGN FOR A CIRCULATING HEATER

Ambrose D. Olds, Wichita, Kans., assignor to The
Coleman Lamp and Stove Company, Wichita,
Kans.

Application August 17, 1936, Serial No. 64,458

Term of patent 7 years

To all whom it may concern:

Be it known that I, Ambrose D. Olds, a citizen
of the United States of America, residing at
Wichita, in the county of Sedgwick and State of
Kansas, have invented a new, original, and orna-
mental Design for Circulating Heaters, of which
the following is a specification, reference being
had to the accompanying drawing, forming a
part thereof.

The figure is a perspective view of a circulating
heater showing my new design. Both sides of
the heater are alike in appearance.

I claim:

The ornamental design for a circulating heat-
er as shown and described.

AMBROSE D. OLDS.
